GRINDING MACHINE

Bertram Charles Spurling, deceased, late of Leicester, England, by Mildred Ann Spurling, administratrix, Leicester, England, assignor to The Bentley Engineering Company Limited, Leicester, England, a British company

Application September 11, 1940, Serial No. 356,388
In Great Britain December 24, 1938

13 Claims. (Cl. 51—100)

This application corresponds to the application of Bertram Charles Spurling and The Bentley Engineering Company Limited, Serial No. 37,569/38 which was filed in Great Britain on December 24, 1938.

This invention consists in improvements in or relating to grinding machines and has for its object to provide an improved machine of this character whereby articles having an irregular outline can be ground with accuracy. It is well known to grind profiles in blanks by causing a carriage which holds a blank to move in a suitable path determined by a pattern while holding the blank against a grinding wheel.

According to the present invention a grinding machine comprises in combination a grinding wheel and a carriage so mounted as to be free to move in any direction parallel to an imaginary plane of reference which is itself parallel to the grinding wheel axis but not away from said plane, a support for attaching a master pattern to the carriage, a support on the carriage for holding a blank to be ground in line with the master pattern in a direction normal to the said plane parallel to which the carriage is movable and presenting it to the grinding wheel, and a stationary guide in line with the grinding wheel in a direction normal to the said plane to engage the profile of the master pattern, so that the carriage can be moved parallel to the said plane to cause the pattern to traverse the guide and thus cause the grinding wheel to reproduce the pattern on the blank.

Other features of the invention will be more clearly understood from the following description of a preferred example of the invention taken in conjunction with the accompanying drawings, in which—

Figure 1 is a perspective view of the apparatus according to the invention;

Figure 2 is a plan of the mechanism illustrated in Figure 1, a portion being broken away for the sake of clearness, and is a section on the line 2—2 of Figure 3;

Figure 3 is an elevation of the apparatus shown in Figure 2, parts being shown in section;

Figure 4 is a section on the line 4—4 of Figure 2;

Figure 5 is a section on the line 5—5 of Figure 2;

Figures 6 and 7 show in elevation a truing device used in conjunction with the grinding wheel, and

Figure 8 is a plan of the device shown in Figure 7.

Like reference numerals indicate like parts in the several figures of the drawings.

The grinding wheel 10 is mounted to rotate about a horizontal axis in a fixed grinding head indicated as a whole by the reference numeral 11 in Figure 1. On a horizontal plane, at a level below that of the grinding wheel, is a fixed table 12 which supports the carriage 13 already mentioned. Between the carriage and the table 12 are ball, roller or other anti-friction devices enabling the carriage to be movable with freedom in all directions in its own plane. In the example shown these antifriction devices comprise a series of balls 14 mounted between outer race rings 15 and inner race rings, not shown, which latter are secured to the under side of the carriage 13. The carriage can therefore move in any direction parallel to an imaginary plane of reference the direction of which is determined by the table 12 so as to be parallel to the grinding wheel axis.

Adjustable on the carriage is a support for a master pattern 16 and this support conveniently takes the form of a shallow channelled member 17 which constitutes the upper member of what is virtually a compound slide rest. The master pattern can be held in the channel by means of bolts 18 or the like and the member 17 is formed on its under side with a key or guide 19 which is guided in a corresponding groove in a companion member 20 lying beneath it. A lead screw 21 rotatably mounted at 22 in an overhanging portion 23 of the member 17 is so mounted that while it is free to rotate it is incapable of endwise movement relatively to the part 23. The lead screw itself engages within a correspondingly threaded recess in the slide member 20 so that by rotation of the lead screw 21 the member 17 can be adjusted towards and away from the grinding wheel. The slide member 20 is formed with side flanges engaging above a slide or guide portion 24 formed on the base of the carriage 13. The flanges on the member 20 and the guide portion 24 are formed to guide movement of the slide 20 in a direction at right angles to the movement of slide 19, and the position of slide 20 on the guide 24 is controlled by means of lead screws 25 situated on each side of the member 20. The lead screws 25 are threaded into correspondingly threaded orifices extending laterally through bearing brackets 26 formed integral with and uprising from the base member 13, and the inner ends of the lead screws 25 abut against the sides of slide member 20.

The brackets 26 support a strong square-sectioned cross member 27, portions of which are cylindrically ground to be carried in bearing sleeves 28 mounted in the upper portions of brackets 26. The bearing sleeves 28 are oppositely tapered as clearly shown in Figure 3 and are held in position by means of nuts 29 each of which is threaded on to the inner end of its sleeve 28 so as to bear against the adjacent surface of bracket 26. The central portion of the cross member 27 is specially shaped as shown clearly in the drawings to afford a rearwardly extending bracket 129 from which rise upstanding lugs 30. Mounted on the bracket 129 in any preferred manner or formed integral with it is a cradle 31 of semi-cylindrical form and in this cradle is carried a two-part work-holder, the lower member 32 of which has its outer surface shaped to conform to the inner surface of the cradle 31. The outer member 33 of the work-holder is mounted in the lower member 32 so as to be capable of sliding in guides therein towards and away from the grinding wheel and if a curved workpiece is to be ground the extremities of the upper work-holder are curved or relieved as at 34. In order to secure the two parts of the work-holder in their adjusted positions, a set screw 35 is screwthreaded into the part 32 and its shank passes through an arcuate slot in the cradle 31 to permit the part 32 to be rocked in its cradle and clamped in any position of adjustment; and another set screw 36 passing through a slot 37 in the member 33 is screw-threaded into the member 32.

The workpiece is shown at 33 and a quick-release device for holding the workpiece in position is constructed as follows: A lever 39 is pivoted between lugs 30 about a pivot pin 40. Screwthreaded into and passing through one end of the lever 39 is an adjustable locking screw 41 and engaging with the opposite end of the lever is a toggle lever 42 pivoted on a pin 43 mounted between lugs 44 extending upwardly from the bracket 129. In the position shown in Figure 4 the toggle lever 43 has been moved downwardly by pressure on a finger-piece 45 so as to force the left-hand end of lever 39 upwardly and thereby to depress the locking screw 41 into firm contact with the workpiece 33 to hold it on the upper member 33 of the work-holder. Previously to clamping the workpiece in position the lower member 32 of the work-holder has been adjusted in cradle 31 to any desired position of angular adjustment. In Figure 5 the quick-release device is shown in its released position for removal of the workpiece.

Mounted in the table 12 is a block 46 carrying a vertical cylindrical guide 47, the axis of which is tangential to the periphery of the grinding wheel and is situated in a position to be engaged by the profile of the master pattern.

It will be seen that in the construction described the carriage 13 can be manipulated by hand, as in the case of any copying machine tool of this type, to maintain the profile of the master pattern in engagement with the fixed guide 47 and by so doing the workpiece 33 clamped in position above the master pattern will be ground to receive a finished profile which is an exact copy of that of the master pattern.

By adjusting the work-holder in cradle 31 the edge of the profile of the workpiece can be relieved, the degree of relief being dependent upon the angular adjustment of the work-holder in the cradle. The latter bears on its end surface

graduated markings to which a fixed pointer on the corresponding end of the member 32 can be set.

The lower slide rest 17, 20, 24 for carrying the master pattern enables an initial adjustment of the position of the master pattern to be made in its setting in the carriage 13.

The carriage may, instead of being mounted for manual movement, be combined with any means by which it may be mechanically or otherwise moved as may be found most convenient.

The work-holder can also be adjusted about the axis of the cross member 27 for which purpose one end of the cross member extending through the left-hand bearing shown in Figure 3 is screwthreaded as at 56 and a locking wheel 57 engages with the screwthread 56, a pressure washer 58 being interposed between the boss of the locking wheel 57 and the outer extremity of bearing 28. The latter is conically formed to engage with a conical recess in the pressure washer. Thus, by loosening locking wheel 57 the cross member 27 can be angularly adjusted to its desired position and the degree of adjustment will be indicated by graduated markings formed on the outer surface of the washer 58 as shown in Figure 1, and these markings can be set against a fixed pointer 59 attached to bracket 26. The washer 58 is caused to turn with the cross member 27 and for this purpose is keyed at 60 to the cross member 27. Thus, to adjust the angular position of cross member 27 the locking wheel 57 will first be loosened, the cross member 27 and the parts it carries will then be adjusted with reference to the fixed pointer 59 after which the locking wheel 57 will again be tightened and the parts will be held firmly in their position of adjustment.

In order to true the grinding wheels from time to time the device illustrated in Figures 6 to 8 is conveniently employed.

The truing device proper comprises a bracket 48 mounted to rotate on fixed guide 47, the parts being carefully machined so that as little play as possible exists in the mounting. Fixed to and extending upwardly from bracket 48 is a standard 49 having a head 50 in which is secured a diamond cutter 51. The latter is conveniently carried at the end of a micrometer screw 52 passing completely through the head 50 from front to back and held in an adjusted position by means of a set screw 53. A handle 54 is screw-threaded into bracket 48 to afford means for swinging the bracket about the fixed guide 47. It will be appreciated that if the cutting point of the diamond 51 is set in vertical alignment with the outer surface of fixed guide 47 and the bracket 48 is swung from side to side about the axis of the guide 47, the edge of the grinding wheel will be true to a curvature conforming exactly with the curvature of the guide 47. As is well known, the grinding wheel may be so mounted that it can be fed towards the truing tool for truing purposes.

In order to set the position of the diamond the bracket 48 can be passed over another rod 55 set apart from the machine and having the same diameter as that of the fixed guide 47. The height of rod 55, however, will be sufficient to extend upwardly beyond the point of the diamond cutter so that the latter can be brought into contact with the surface of rod 55, whereupon the set screw 53 will be tightened to hold the diamond in the position thus set. This will

ensure that when the bracket 48 is transferred on to fixed guide 47 the vertical alignment of the diamond cutter and the outer surface of guide 47 will be ensured.

What is claimed is:

1. A grinding machine comprising in combination a rotatable grinding wheel and a carriage, means mounting said carriage for movement in any direction parallel to and at a fixed distance from an imaginary plane parallel to the grinding wheel axis, a support on the carriage for attaching a master pattern thereto out of the plane of the axis, a support on the carriage for holding a blank to be ground in a position for presentation to the grinding wheel in line with the master pattern in a direction normal to said imaginary plane and in the plane of said axis, and a stationary guide positioned to engage the profile of the master pattern, in line with the grinding wheel periphery in a direction normal to said plane, whereby movement of the carriage parallel to the said plane will cause the pattern to traverse the guide and cause the grinding wheel to reproduce the pattern on the blank.

2. A grinding machine as claimed in claim 1 in which the support for attaching the master pattern to the carriage comprises crossed slides on the carriage and means to individually adjust said slides so that the master pattern may readily be positioned to any desired relationship with the means for holding the blanks.

3. A grinding machine as claimed in claim 1 in which the support for holding the blank includes means adjustable in relation to the carriage about two axes at right angles to each other, one of said axes being at right angles to the axis of the grinding wheel when the carriage is in its normal relation to the wheel.

4. A grinding machine as claimed in claim 1 wherein the support for holding the blank is mounted on a shaft, means rotatably supporting the shaft from the carriage with its axis parallel to the plane of reference of the carriage-motion, and parallel to the grinding wheel spindle.

5. A grinding machine as claimed in claim 1, including a quick-release device associated with the support for holding the blank thereon for the purpose of clamping and releasing the same as desired.

6. A grinding machine as claimed in claim 1, wherein the mounting means for the carriage is a flat supporting plate, whereby universal movement thereof is effected by moving the carriage over the plate.

7. A grinding machine as claimed in claim 1, wherein the supporting means for the carriage is a flat plate, and antifriction bearing members interposed between the supporting plate and the carriage.

8. A grinding machine as claimed in claim 1, wherein the supporting means for the carriage is a flat plate, and ring ball bearings interposed between the carriage and the supporting plate.

9. A grinding machine as claimed in claim 1 in which the support for the blank comprises a cylindrical cradle mounted on said carriage and a corresponding cylindrical work-holder adjustable therein, the axis of the cylinder being normally disposed at right angles to the axis of the grinding wheel, for the purpose described.

10. A grinding machine comprising in combination a grinding wheel rotatable about a fixed axis, a fixed flat supporting plate having an upper surface parallel with the axis of the grinding wheel, a carriage mounted on the supporting plate for movement in any direction over the surface thereof, means on the carriage for adjustably supporting a master pattern, a guide having a guiding surface positioned so as to be capable of engagement with the master pattern and extending in a direction at right angles to the supporting plate and tangential to the edge of the grinding wheel, a cradle upon the carriage including clamping means for a blank to hold the same for grinding by said wheel and means adjustable to cant the blank, one of said means being adjustable about an axis parallel to the supporting plate and the other about an axis at right angles to the wheel axis so as to present the blank to the grinding wheel at any desired inclination while keeping the master pattern engaged with the stationary guide.

11. A grinding machine as claimed in claim 10 including a quick-release device associated with the cradle for holding the blank thereon for the purpose of clamping and releasing the same as desired.

12. A grinding machine as claimed in claim 10, including anti-friction members inserted between the supporting plate and the carriage.

13. A grinding machine as claimed in claim 10, including ring ball bearings inserted between the supporting plate and the carriage.

MILDRED ANN SPURLING,
*Administratrix of the Estate of Bertram Charles
Spurling, Deceased.*
